UNITED STATES PATENT OFFICE.

DALLAS F. GREEN, OF FORT WAYNE, INDIANA.

DESIGN FOR A FINGER-RING OR SIMILAR ARTICLE.

51,981.

Specification for Design.

Patented Apr. 23, 1918.

Application filed February 14, 1918. Serial No. 217,246. Term of patent 14 years.

To all whom it may concern:

Be it known that I, DALLAS F. GREEN, a citizen of the United States, residing at Fort Wayne, county of Allen, and State of Indiana, have invented a new, original, and ornamental Design for Finger-Rings or Similar Articles, of which the following is a specification, reference being had to the accompanying drawing, forming part thereof.

Figure 1 is a three-quarters perspective front view of a ring showing my new design.

Fig. 2 is a side elevational view, and

Fig. 3 is a three-quarters rear perspective view.

I claim:

The ornamental design for a finger ring or similar article, as shown.

DALLAS F. GREEN.
